UNITED STATES PATENT OFFICE.

ERNST G. K. ANDERSON, OF CHICAGO, ILLINOIS, ASSIGNOR, BY MESNE ASSIGNMENTS, TO APPLETON ELECTRIC CO., OF CHICAGO, ILLINOIS, A CORPORATION OF ILLINOIS.

ELECTRIC SWITCH.

Application filed June 25, 1921. Serial No. 480,347.

This invention relates to improvements in electric circuit controlling switches, and refers more particularly to a novel switch mechanism and mounting which adapts it to be enclosed in relatively small compass in a structure which protects the mechanism from the elements, while permitting the actuator for the switch to be conveniently brought to the exterior of the enclosure. The embodiment of the invention herein shown is adapted to control the lamp circuits of so-called universal spot lamps, and in this installation said mechanism may be enclosed by and supported in the rearwardly extending stem of the lamp structure by which the lamp structure can be suitably adjusted about the axes of the universal mounting for the lamp.

Among the objects of the invention is to produce a simple, economical, and compact switch mechanism of the character that is capable of being so enclosed and supported and so arranged with respect to the mounting that the switch can be manually controlled or can be automatically controlled by means which are operative upon relative motion of the members of the universal movement.

A further object of the invention is to provide a switch mechanism of this character, the circuit closing elements of which are so constructed as to be arranged and supported in an elongated compact closure of such character as to protect the elements of the switch mechanism from the weather and also from derangement due to external shocks and bruises.

Another object of the invention is to provide a novel means for actuating the switch elements, so constructed that the actuator can have simple movements, and also so arranged with respect to the enclosure that the actuator can be extended through the closure wall while maintaining a weather-proof joint between the actuator and closure.

Another object of the invention is to provide a switch mechanism and a tubular mounting therefor of the character described, wherein the operative switch elements are partially supported by the lamp socket at one end of said support and can be removed with the socket endwise from one open end of the elongated closure and support.

Other objects of the invention are to improve and simplify switch mechanisms for this and for other purposes, and the invention consists in the combination and arrangement of the parts shown in the drawings and described in the specification, and is pointed out in the appended claims.

In the drawings:

Figure 1 is a partial plan and partial sectional view of a switch embodying my invention.

Figure 2 is a section taken on the line 2—2 of Figure 1, with parts shown in elevation.

Figure 3 is a partial rear elevation, with parts broken away, and with parts in section.

Figure 4 is an enlarged detail section on the line 4—4 of Figure 2.

Figure 5 is a fragmentary enlarged sectional detail of the blades and the actuator and associated parts.

Figure 6 is a detail plan view of some of the parts shown in Figure 5.

Figures 7, 8, and 9 are details of insulating and supporting elements for the switch mechanism.

Figure 10 is a longitudinal section of one of the switch blades, hereinafter to be described.

Figure 11 is a partial horizontal section and partial plan view of another type of lamp mounting showing my improved switch mechanism embodied therein.

Figure 12 is a section on the line 12—12 of Figure 11, with parts in elevation.

The switch mechanism is shown in Figures 1 to 4, inclusive as applied to a type of universal spot lamp which includes as one of its features a reel on which the lamp cord is wound when the lamp is supported at its normal station on the car or other place where it is to be used, and from which reel the cord is adapted to be unwound when the lamp is removed or extended from its normal support. In Figures 11 and 12 said switch mechanism is shown as applied to a simpler form of universal spot lamp mounting.

First referring to the construction shown in Figures 1 to 10, inclusive, 10 designates a single shell lamp casing having an interior reflector, 11 an electric lamp located in the focal axis of the reflector, and 12 a hollow

stem which is fixedly attached at its forward end to the casing and extends rearwardly therefrom to constitute means for directing the lamp in its universal movements. Said stem is hollow to receive the lamp circuit switch mechanism. 13 designates the casing for containing the cord rewinding reel such, for instance, as is shown in my prior United States Patent Number 1,309,678, issued on the 15 day of July, 1919. Said casing may have means of attachment to a suitable support, such as the post of a windshield frame, when used on a motor vehicle. The universal lamp mounting embraced in the structure shown in Figures 1, 2, and 3, comprises an elbow fitting 15 having a horizontal arm 16 and a vertical arm 17. It is hollow to constitute a conduit for the passage of the lamp cord 18 from the casing 13. The terminal of said vertical arm 17 has a tapered rotational bearing connection with the fixed bracket ring 19 that supports the reel structure casing and through the medium of which the mounting is attached to a fixed support, and said tapered bearing elements are forced together by a nut 20, as shown in Figure 3. The rotational joint between the arm 17 of the elbow fitting 15 and the supporting member for the reel casing permits the lamp to be adjusted in a horizontal plane by the application of moderate manual power.

Between the horizontal arm 16 of said elbow fitting and the stem 12 of the lamp casing is a rotational joint which permits vertical adjustment of the lamp casing. It embraces a stud 28 integral with and at a right angle to the stem 12, and the stud is reenforced by a metal insert sleeve 29 which is formed beyond the stud with a tapered extension 30. The arm 16 of said elbow fitting is slotted, as indicated in dotted lines at 31 in Figure 1. It fits over the external taper of said extension and is externally threaded at its tapered portion to receive a nut 32 that is formed at its screw thread with a taper that is opposed to the taper of the extension. Said nut locks the parts of the joints together while permitting rotational movement of said parts to allow vertical adjustment of the lamp structure.

The base 35 of the lamp 11 fits within a socket 36 which is slidingly mounted in the end of the stem adjacent to the casing 10. Said socket and lamp carried thereby may be axially shifted for focal adjustment and locked in adjusted positions.

Referring now to the switch mechanism embracing the present invention, 44, 44 designate conductor terminal bars which are fixedly attached to and extend rearwardly from and are supported on the rear end of the socket 36. As herein shown, said bars are provided with right angled feet 45 which lie flat against an insulating disc 46 on the

rear end of the socket and are pierced for the extension therethrough of the terminal ends 48 of the lamp socket contacts 49, illustrated in full lines in Figure 12, the terminals being suitably swaged over the feet 45. 70

50 designates a flat insulating supporting body which is disposed longitudinally of the enclosing casing 12 for the switch mechanism. It extends at its front end between the terminal bars 44 and is attached to said bars between the ends of the latter by means of the rivets 51. 52, 52 designate resilient switch blades which are disposed in a generally longitudinal relation to said insulating support 50. Said blades are attached at 75 their rear ends to said insulating support by means of hollow rivets or eyelets 53, 53 (Figure 4). One end of each eyelet is upset over one of the switch blades 52 to form a head 54 that has good electric contact with the associated blade. The other end of each eyelet is flanged to form a head 56 to engage the opposite side of the insulating support remote from said blade. With this construction it will be noted, from an inspection of Figure 4, that each hollow rivet or eyelet 53 fixes one of the blades to the insulating support, and that said support constitutes an insulating barrier between said switch blades. It will also be observed that the said insulating support constitutes means to partially sustain the blade assembly from the rear end of the lamp socket 80. 95

58, 58 designate shorter insulating strips, one of which overlies and the other of which underlies the insulating support 50, and are, therefore, interposed between the blades and said support. Said strips 58 are respectively attached to said support 50 by the flanged or headed ends 54 of the eyelets 100 53. The said insulating strips terminate at their forward, free ends at shouldered portions 59 of the switch blades in rear of the contact ends 60 of said blades that are adapted, when the blades spring towards each other, to engage on the terminal bars 44 of the socket contacts and to thereby close the lamp circuit. The branches 61 of the conductor cord 18 are stripped at their ends to extend into the eyelets 53 in any suitable manner and are fixed to said eyelets by current conducting solder joints 62, whereby each of said branch conductors is connected to one of the switch blades. 110 115

A preferred form of switch blade is shown in Figures 1 and 10, wherein the blade, made of resilient current conducting material, is formed between its ends with a longitudinal strengthening rib 63 to reinforce or stiffen it, and is formed near its contact end 60 with an indentation or lug 64 to engage in a notch or aperture 65 at one side of and near the adjacent end of the associated insulating strip 58 (Figures 7, and 9). Figures 7, 8, and 9, considered in con- 120 125 130

nection with Figures 1 and 4, illustrate a convenient mode of grouping the insulating support and strips, which support and separate the blades. As therein shown, the outer or free end of the support 50 is provided with two apertures 67 for the passage of the eyelets 53, and the insulating strips 58 are provided near their outer ends with apertures 68, so that when the said strips 58 are laid one over and one under the insulating support 50, the apertures 68 will match with the apertures 67 for the passage of the rivets or eyelets 53. In the complete switch assembly the said eyelets 53 also extend through apertures 52 at the fixed or heel ends of said switch blades. The said insulating support is formed at its front end with apertures 69 for the passage of the rivets 51 by which the said support is fastened to the socket contact terminal bars 44. The manner shown of attaching the switch blades to the insulating support causes said blades to assume a relative crosswise relation, as shown in Figure 1. It is not essential (though desirable) that said blades assume this crosswise relation, it only being desirable that they extend at each side of the insulating support, or its equivalent, towards and for contact with the terminal bars 44, so that said blades may properly close on said terminal bars to close the switch, and may be spread apart or separated by the means hereinafter described to open the switch at their contact ends 60.

The attachment of the switch blades 52 to the rear end of the insulating support 50 is such that the ends of said blades are normally pressed against the socket contact terminals 44 to close the lamp circuit. The said blades are adapted to be forced or spread away from said terminal bars to open the circuit by a switch actuator element having a part that lies between the switch blades, and adapted, upon suitable actuation thereof, to spread said blades from each other and to thereby open the circuit.

The actuator element shown in the present instance consists of a pin 71 which extends at its inner end transversely across the space between the blades 52. To this end the adjacent side of the support 50 is cut away between the ends to form a recess 50' to receive the inner end of the actuator pin. The outer end of said pin has rocking and axial bearing movement in ears or lugs 73, shown as integral parts of the stem 12 and stud 28. Between said ears or lugs an arm 74 extends from said pin 71 to constitute an actuating arm, through which to impart rocking movement to the pin. The recess or space between said lugs or ears is of a width to permit clearance space for the arm 74 of the actuator ele-

ment when the said element is axially shifted to control the movements of the switch blades.

The inner end of the actuator pin 71 is formed with a terminal 77 which is of oblong cross-section. That is to say, said terminal is made of substantially greater width than depth, as is clear by an inspection of Figures 5 and 6. When the smaller dimension thereof is presented towards the blades, as shown in Figure 5, the terminals of the blades are free, by reason of the resiliency thereof, and their fixed mounting at their outer ends, to move into contact with the socket contact terminals 44. When said pin is rocked 90° the wider portion of the end of the pin is presented towards the blades, as shown in Figures 2 and 12 to open the circuit between said blades and terminals by spreading the blades apart.

In order to avoid destructive wear between the rectangular portion of the actuator pin and the insulating strips 58 a U-shaped wear member 73' is fitted over the intermediate portion of the insulating support 50 at the recess 50' thereof so as to lie between the end of the pin and the insulating strips 58 (Figures 1, 5 and 6). Said wear plate is made of a length, longitudinally of the support 50 to fill said recess 50' of said insulating support. The support 50 is notched at 50² and the insulating strips 58 are likewise notched at 58' to receive the closed portion of the U-shaped wear plate or member 73' so that the parts will be flush with each other. Preferably the closed end of the wear plate is recessed at 73² to increase the flexibility thereof.

The end margins of the arms of the said U-shaped wear plate are flared outwardly in opposed relation to form tapered faces or lips 78 to engage tapered faces 79, 79 formed between the cylindrical portion of the actuator pin and the rectangular end thereof. Contact of the tapered and flaring portions of the actuator pin and wear plate, respectively, has the effect, when the pin is pushed inwardly, to spread the switch blades apart and open the switch. The switch will remain open so long as operating pressure is maintained on the pin. When the pressure is relieved, however, the resiliency of the blades and wear plate 73' will force the actuator pin outwardly, whereupon the blades will close on the terminals 44. Operation of the switch through such axial movement of the pin has been designed to be effected by an automatic control, such as is shown in my United States Letters Patent Number 1,462,473, granted on the 24th day of July, 1923. The switch, when opened by rocking movement of the pin 71, is operated by hand, and, owing to the flattened faces of the end 77 of said pin, the pin remains in a given adjustment until

intentionally varied by manual power. When the switch is thus opened by rocking movement of the pin and remains open, axial movement of the pin will have no effect on 5 the switch control.

With the construction described, it will be observed that when the said actuator element or pin 71 is rotated on its axis, rocking of the oblong rectangular portion there- 10 of will serve to present its widest part to- wards the arms of the U-shaped wear plate 73' to thereby act, through the insulating strips 52, to spread the blades and open the circuit between the ends of said blades and 15 the terminals 44. Likewise when said actuator pin is moved axially the tapered or wedge faces 79 thereof, acting against the flaring margins 78 of the wear plates, serve to spread said arms and to thereby, in a like 20 manner, spread the switch blades away from the terminals 44 and open the switch.

The outer ends of the insulating support 50 and the strip 58 are of widths to sub- 25 stantially fill the hollow stem or enclosure, as shown best in Figure 4, whereby the switch mechanism is supported from both ends of the stem or enclosure. However, the said mechanism is free to be withdrawn from the stem or enclosure, together with 30 the socket, when the stem is open at its front. The construction also facilitates the assemblage of the switch, inasmuch as it can be assembled as a unit, except for the actuator pin 71, and the latter can be readily inserted in the assembled switch.

The application of the switch mechanism to a lamp of the character shown is a de- 40 sirable one, inasmuch as the switch is effi- ciently protected from the elements and from shocks and bruises, and can thus be enclosed in a compact space which otherwise would not be used. Therefore, the combination is an efficient and effective one. Moreover, the arrangement is one which conveniently 45 lends itself to the automatic control shown and claimed in my aforesaid Letters Patent No. 1,462,473.

Figures 11 and 12 illustrate equal adaptability of said switch mechanism to a simpler form of universal mounting, wherein the 50 reel structure and function is omitted. The universal movement functions of the structure shown in said Figures 11 and 12 are embraced in a hinged joint 80 between a bracket member 81 adapted for means of 55 attachment to a fixed support, and a rotational joint 83, whose movement is an axis at a right angle to the axis of the hinge joint or connection 80.

60 I claim as my invention:

1. In an electric switch, the combination with spaced terminals, insulated from each other, and spaced, generally parallel blades fixed at one end of the switch and springable 65 towards each other and said terminals to

close the switch and insulated from each other, of a rocking and reciprocating actuator adapted to extend between said blades and having a spreader end shaped to spread the blades apart when the actuator is either 70 rocked or reciprocated.

2. In an electric switch, the combination with spaced terminals, insulated from each other, and spaced, generally parallel blades fixed at one end of the switch and spring- 75 able towards each other and said terminals to close said switch and insulated from each other, of an axially and angularly movable actuator adapted to extend between said blades, and formed with tapered surfaces 80 adapted to engage tapered surfaces on a part between said switch blades.

3. In an electric switch, the combination with spaced terminals insulated from each other, and spaced, generally parallel blades fixed at one end of the switch and spring- 85 able at one end towards each other and said terminals to close the switch and insulated from each other and mutually supported at their other ends, of an axially movable actuator adapted to extend transversely between said blades, and a U-shaped member between said blades having at one side flaring margins and the actuator having a tapered end 90 to operate, in axial movement of the actuator, between the flaring margins of said U- shaped member to spread said blades.

4. In an electric switch, the combination with spaced terminals insulated from each other, and spaced, generally parallel blades fixed together and insulated from each other at one end of the switch and springable to- 100 wards each other and said terminals to close the switch, of a U-shaped member trans- versely between said blades having parallel arms formed with outwardly flaring por- 105 tions, and an axially movable and rocking actuator having a part of oblong cross section fitted between said arms and having a 110 tapered part to engage the flaring portions of said arms.

5. In an electric switch, the combination with spaced terminals, a flat blade support- 115 ing member of insulating material fixed be- 120 tween and supported by said terminals and extending therefrom, and elongated blades fixed at corresponding ends to said support and thereby insulated from each other and springable at their free ends toward said terminals, of spreader means acting on said blades between their ends to spread said blades out of contact with said terminals.

6. An electric switch and its hollow elongated case, the latter adapted at one end to receive a lamp socket, which upon removal opens one end of said case, and said socket being provided with socket contact terminals, generally parallel switch blades insulated from each other and adapted for contact with and springable toward said socket 125 130

- terminals, and adapted as a unit to be withdrawn from the case through said open end, and a rocking and axially movable actuator element extending through the wall of said case and transversely between the switch blades and constructed at its inner end to spread the blades apart upon both axial and rocking movement to open the circuit between the blades and said terminals.
- 10 7. A switch mechanism and its hollow elongated case, the latter open at one end to receive a lamp socket provided with rearwardly directed terminals, an elongated, insulating support fixed between said terminals and extending rearwardly through the case, said insulating support being sustained at one end by said terminals and supported on, but free from attachment at its other end to the case wall, switch blades attached at their rear ends to said support and thereby insulated from each other, said blades being normally springable toward said terminals, and an actuator extending through the wall of the case, having an inner spreader end to 20 act on both rocking and axial movement of the actuator to spread the blades apart and out of contact with said socket terminals.
8. A switch mechanism and its hollow elongated enclosure, the latter open at one end to receive a socket provided with rearwardly directed terminals, an insulating support fixed to and between, and partially sustained by, said terminals and extending rearwardly therefrom, and switch blades mounted on said insulating support and thereby insulated from each other and adapted to close on said terminals, said insulating support being otherwise unattached and the switch blades being movable with 30 said support to be moved endwise from the case with said socket.
9. A switch mechanism and its hollow elongated case, the latter open at one end to receive a socket provided with rearwardly directed spaced terminals, an elongated insulating support fixed to said socket between said terminals and extending rearwardly therefrom, switch blades fixed at their rear ends to said support and thereby insulated from each other and springable towards each other and said terminals to close the switch, and an actuator extending through the wall of the case and having rocking and axial movement therein and provided at its end 40 between said blades with an oblong cross sectional terminal and exterior to said terminal with tapered or wedge faces to engage corresponding faces of parts that act with a spreading effect on said blades to open said switch.
10. A switch mechanism and its hollow elongated case, the latter open at one end to receive a socket provided with rearwardly spaced terminals, an insulating support fixed to and between, and partially 50 supported on, said socket and extending rearwardly therefrom, switch blades, insulating strips lying between said insulating support and said blades, with means to fix the rear ends of said blades to said strips and insulating support, said blades being normally springable at their other ends toward said terminals, said insulating body and strips being notched between their ends, a U-shaped wear plate fitted to the notched portions of said insulating support and strips, and an actuator member extending through the wall of the case and having an oblong cross-section terminal fitted between the arms of said U-shaped wear plate.
11. A switch mechanism and its hollow elongated case, the latter open at one end to receive a socket provided with rearwardly spaced terminals, an insulating support fixed to said socket between said terminals and extending rearwardly therefrom, switch blades, insulating strips lying between said insulating support and said blades, with means to fix the rear ends of said blades to said strips and insulating support, said blades being normally springable at their other ends toward said terminals, said insulating body and strips being notched between their ends, a U-shaped wear plate fitted to the notched portions of said insulating support and strips, and an axially movable and rocking actuator member extending through the wall of the case and having an oblong cross section terminal fitted between the arms of said U-shaped wear plate, said wear plate extending beyond said insulating support and provided at its open side with flaring margins, and the actuator member being provided with corresponding tapered portions to fit the flaring margins of said wear strip.
12. In a switch mechanism, the combination with a fixed, elongated insulating support, with terminals fixed thereto and insulated from each other thereby, of switch blades extending longitudinally of said support and insulated from each other thereby, insulating strips lying between said insulating support and said blades, means to fix the rear ends of said blades to said strips and insulating support, with the said blades normally springable against said terminals, said insulating body and strips being recessed between their ends at their overlying portions, a U-shaped wear member fitted to the cut away portions of said insulating support and strips, and bearing against said strips, and an actuator member having a spreader terminal fitted against the arms of said U-shaped wear member, provided near their contact ends with positioning indentations which are seated in apertures of said insulating strips.
13. The combination with a hollow stem having an opening at the casing to receive

a lamp socket provided with rearwardly directed terminals, of an elongated insulating support fixed to said socket and extending rearwardly within said stem, switch blades carried by said support and insulated thereby from each other, said blades being springable towards each other and said terminals for contact with the latter, and an actuator extending through and 10 having axial and rocking movement in said

stem, the inner end of said stem lying between said blades and formed to constitute a spreader element that is operative to spread the switch blades from each other to open the switch upon both axial and rocking movement of said actuator. 15

In witness whereof I claim the foregoing as my invention, I hereunto append my signature this 13 day of June, 1921.

ERNST G. K. ANDERSON.
